(57) **CLAIM**

The ornamental design for a materials handling vehicle, as shown and described.

DESCRIPTION

FIG. 1 is a front perspective view of materials handling vehicle, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view of the materials handling vehicle taken through line 9-9 in FIG. 3 and along the direction of the arrows at the two ends of the line 9-9; and, FIG. 10 is a cross-sectional view of the materials handling vehicle taken through line 10-10 in FIG. 3 and along the direction of the arrows at the two ends of the line 10-10.

The broken lines in the drawings illustrate the portions of the materials handling vehicle that form no part of the claimed design.

1 Claim, 10 Drawing Sheets
